UNITED STATES PATENT OFFICE.

JOHN O. CARREY, OF ST. LOUIS, MISSOURI, ASSIGNOR TO CARREY PROCESS COMPANY,
ON ST. LOUIS, MISSOURI, A CORPORATION OF MISSOURI.

APPARATUS FOR SEPARATING MECHANICAL MIXTURES OF GASES.

1,248,454.

Specification of Letters Patent.

Patented Dec. 4, 1917.

Application filed April 10, 1915. Serial No. 20,556.

To all whom it may concern:

Be it known that I, JOHN O. CARREY, a citizen of the United States, and residing at the city of St. Louis and State of Missouri, have invented a new and useful Apparatus for Separating Mechanical Mixtures of Gas, of which the following is a specification.

This invention relates to a new and useful apparatus for separating mechanical mixtures of gas.

An object of the invention is to provide a suitable apparatus for effecting the mechanical separation of volumes of gases in a mechanical mixture, into separate volumes composed of the component gases of the mixture.

With the foregoing objects and additional features and advantages attainable from the present invention in view, I have designed an apparatus as shown in the accompanying drawings and hereinafter disclosed in detail.

In the accompanying drawings—

Figure 1 is a side elevation of an apparatus particularly adapted for practising the improved process of the invention.

Fig. 2 is a similar view with the lower portion of the apparatus being shown in section.

Fig. 3 is a cross section through the apparatus taken substantially on the line 3—3 of Fig. 2.

Fig. 4 is a cross section taken substantially on the line 4—4 of Fig. 2, and

Fig. 5 is a cross section taken substantially on the line 5—5 of Fig. 2.

In the construction of the apparatus as illustrated in the drawing I have shown a frame work comprising uprights 1 a bottom member 2 and an arched top 3. A main operating shaft 4 is supported in the frame work, said shaft being journaled in bearing brackets 5, 6 and 7, respectively. The bracket 6 is bolted to the side members 1 of the frame, substantially intermediate of the top and bottom thereof, to give rigidity to the frame and to maintain the proper alignment of the shaft.

A receiving chamber A having an annular wall 8 and a cap or closure 10, is supported rigidly within the frame member by integrally formed brackets 9. In order to seal the joint between the cap 10 and the wall 8 I provide the upper edge of the wall 8 with an overhanging bead 11, which is adapted to seat within a groove or channel

formed in an annular ring 12 which ring is in threaded engagement with the edge of the cap 10. A quantity of oil is placed within the groove or channel in the ring 12 to effect an oil seal of the joint and also to provide a lubricant, so that the cap 10 may turn without friction about the edges of the wall 8.

A chamber B is arranged below the receiving chamber A and comprises an annular side wall 13, a top wall 14 and a bottom wall 15. A sealed joint is provided between lower edge of the chamber A and the upper face of the chamber B. The construction for effecting the seal comprises a trough formed on the upper wall of the chamber B by an annular vertical flange 16 and an annular ring 17 in threaded engagement with a second ring 18 carried by the top plate 14 of the chamber B. A flange 19 formed at the lower edge of the wall 8 extends into said trough. It will be understood that a quantity of oil is provided in said trough effectively to constitute an oil seal as well as to provide a lubricant preventing friction as the chamber B is rotated.

At the center of the chamber B is a hub member 20 through which the shaft 4 extends. The hub member is releasably secured to the shaft 4 by a set screw 21 or other suitable binding device. A series of blades or vanes 22 connected with the hub member and extending radially therefrom are provided for the purpose of agitating the contents of the chamber. In the top wall 14 of the chamber B and encircling the upper edge of the hub 20 is a series of openings 23, providing passage-ways between the chambers A and B.

The lower wall 15 of the chamber B is in the form of a circular plate in which is formed a plurality of concentric circular series of openings 24, 25 and 26, respectively. The openings are arranged in series on parallel spaced circles and are adapted to provide ports or outlets for the separated gases in different vertical zones, as will be more fully explained hereinafter.

Below the chamber B is arranged a series of chambers C, D and E, respectively. The chambers C, D and E are located within a common annular side wall 27 which is supported rigidly in the frame by brackets 28, and are disposed, respectively, between a top wall 29, partition walls 30 and 31 and 110.

a bottom wall 32. Separate independent passages leading to the respective chambers C, D and E from the chamber B are provided, each of the passages opening adjacently respectively to the series of outlet ports 24, 25 and 26. The independent passages just mentioned are separated by partition walls 33, 34 and 35, respectively. The wall 33 is a dish-shaped structure the lower edge of which is curved to form a tongue 36, which is adapted to seat in a groove formed between the inner upturned edge of the wall 29 and an annular ring 37 carried by the upper face of the wall 29 with which it has threaded engagement. The wall 33 is L-shaped in cross-section and has threaded engagement at its upper end with the wall 15 and has one leg thereof extending downwardly terminating in a tongue which is adapted to seat in a groove of substantially the same structure as that just described. The wall 34 extends downwardly below the edge of the depending portion of the wall 32 and is provided with a tongue at its lower edge adapted to seat in a groove of the same construction as that above described. The construction of the joints between the walls 32, 33 and 34 and the respective walls forming the chambers C, D, and E, that has just been described is such that a seal is provided between the respective partition walls which turn with and may be considered as a part of the chamber B and the stationary chambers C, D and E. It will also be understood that oil is provided in the grooves that have been described, for the purpose of effecting the sealing of the joints and also of lubricating the parts, permitting the same to operate with a minimum degree of friction. In order to effectively seal the opening in the center of the bottom wall 32, I provide a cap member 38 releasably secured to the shaft 4 which cap has inclined edges adapted to operate in oil containing troughs formed between the inclined edges of the wall 32 surrounding the opening and a member 39 in threaded engagement with the threaded edges of said opening.

A number of exhausters 40, 41 and 42 are mounted in the upper part of the frame. The rotors of the exhausters are connected to and actuated by the shaft 4. The exhausters are connected respectively with the chambers C, D and E, by conduits or pipes 43, 44 and 45.

A conduit 46 connected into the chamber A and leading from the container for the mixed gases is provided, and constitutes a supply conduit whereby the gases to be separated may be introduced into the receiving chamber.

Service conduits 47, 48 and 49 leading from the exhausters provide means for conducting the separated gases to storage containers or other receivers for use.

A belt pulley 50 is mounted on the shaft 4, whereby power from any suitable source may be provided for driving the shaft and actuating the apparatus.

From the foregoing it will be understood that the process of separation of mechanical gases is practised on the apparatus as follows.

The mixed gases are drawn into the chamber A from the conduit 46, from whence they pass into the chamber B.

The shaft 4 is rotated at a high speed thereby revolving the vanes or blades 22 and the chamber B at a high velocity. The volume of mixed gas introduced into the chamber B is subjected to the whirling action of the blades 22 and chamber B thereby, through centrifugal action, causing the heavier gas to move to the outer zone of the chamber, the lighter gas remaining in a zone adjacent to the axis of the revolving chamber, with the imperfectly separated strata being in the intermediate zone. From the several zones the now separated gases pass from the bottom of the chamber B into the several receiving chambers C, D and E, respectively, from whence they are drawn by the exhausters through the conduits 43, 44 and 45 and discharged into the service passages 47, 48 and 49, to be conducted to separate receiving chambers.

Having thus fully described my invention; what I claim and desire to secure by Letters Patent is.

1. An apparatus for separating mechanically mixed gases, comprising a frame, a receiving chamber mounted in said frame, a revoluble power shaft journaled in the frame, a chamber carried by said power shaft and located adjacently to said first-mentioned chamber, a passage from said first-named chamber to said revoluble chamber, a plurality of outlet passages from said second-named chamber discharging from different radial zones and devices for establishing a suction in the outlet passages, whereby the separate volumes of gases are drawn from said chamber, substantially as specified.

2. An apparatus for separating mechanically mixed gases, comprising a rigid frame, a receiving chamber mounted rigidly in said frame provided with a supply passage, a revoluble shaft carrying a chamber, blades in said last-named chamber, a passage from the first-named chamber to said last-named chamber, a seal between said two chambers, and a plurality of outlet passages from the second-named chamber discharging from different radial zones, whereby the separated volumes of gases may be conducted from said chamber, substantially as specified.

3. An apparatus of the class described, comprising a main frame, a receiving chamber mounted in said frame provided with

2. supply passage, a revoluble power shaft in said frame, a hollow drum carried by said power shaft and constituting a revoluble chamber, a seal between said drum and said receiving chamber, blades carried by said shaft and disposed within said frame, a plurality of chambers for receiving the separated volumes of gases carried by said frame, and conduits leading from said revoluble chamber to the separated ones of said last-named chambers, substantially as specified.
3. In an apparatus of the class described, a revoluble drum constituting a separating chamber, a plurality of outlets discharging from said separated radial zones leading from said revoluble chamber, exhausters in communication with said outlet passages for withdrawing the separated volumes of gases from said revoluble chamber, substantially as specified.
4. In an apparatus of the class described, a main frame, a receiving chamber rigidly supported in said frame, a revoluble chamber in communication with said receiving
- chamber, a seal between said two chambers, 25 a plurality of discharge passages from said revoluble chamber discharging from different radial zones, and exhausting devices in said discharging passages for withdrawing the separated volumes of gases from 30 said revoluble chamber, substantially as specified.
5. In an apparatus of the class described, a frame, a revoluble shaft mounted in said frame, a drum carried by said shaft, blades 35 mounted upon said shaft and extending into said drum, an inlet passage entering said drum, a series of discharge passages discharging at separate radial points, and exhausting devices in the discharge pas- 40 sages, substantially as specified.
- In witness whereof I have signed this specification in the presence of two subscribing witnesses.

JOHN O. CARREY.
